UNITED STATES PATENT OFFICE.

WILLIAM TABKEN, OF LEDBETTER, TEXAS.

DESIGN FOR A FENCE-POST.

SPECIFICATION forming part of Design No. 31,800, dated November 7, 1899.

Application filed October 10, 1899. Serial No. 733,219. Term of patent 7 years.

To all whom it may concern:

Be it known that I, WILLIAM TABKEN, a citizen of the United States, and a resident of Ledbetter, in the county of Fayette and State of Texas, have invented and produced a new and original Design for a Fence-Post, of which the following is a specification, reference being had to the accompanying drawing, forming a part thereof, comprising a perspective view of a fence-post, showing my new design.

As shown in the drawing, the leading or material feature of my design consists of the flanges at the edges of the post, with their openings, and the base-piece turned at right angles to the post.

My design consists of the vertical wall *a*, having flanges *b* and *c* formed at its vertical edges and extending at right angles thereto. In the flange *b* are formed vertical slots *d*, hav-

ing upwardly-directed leading-in passages *e*, 20 and in the flange *c* are vertical slots *f*, corresponding to the slots *d* and having downwardly-inclined leading-in passages *g*. At the base of the vertical wall *a* is a rearwardly-extending foot *h*, and above said foot in the wall 25 *a* are formed a number of perforations *i*.

Having thus described my invention, what I claim as new, and desire to secure by Letters Patent, is—

The design for a fence-post as herein shown 30 and described.

In testimony whereof I affix my signature in the presence of two witnesses.

WILLIAM TABKEN.
